Wood Planing Machine.

Patented Mar. 8, 1806.

Joseph Mallalieu

Portsmouth

The machine is to be used for the purpose of planing and making
planks of timber, or containing a number of planks, in other words of
the name of Joseph Mallalieu himself of his joining and
planing machine.

This machine consists of the following parts.

1°. A spur wheel running in the work shop. This spur
or large wheel is to operate on your ordinary carriages, moving in
grooves of a length admitting of their passing each other
on this spur wheel may run outside of the shop in the
sides of which an opening being made the carriage may
work the carriage within.

2°. Above each carriage is fixed a rack containing a
any number of planes placed in the rabbled bars which
form the racks. Each rack of planes being placed the
thickness of a shaving lower than the one before and in such
manner that the thickness of planes shall be even
taken off the shavings left by the planes between each of
the planes of the preceding racks. The planes are to be
rabbled cross bars having a shoulder to stand on the
face which is thus sunk even with or below the bar before
each plane are suspended to carry off sand & dirt, which
might injure the planes. The front of each plane should
be bent back off the front edge in order to receive it on the
bars.

At the end of each rack there should be planing gauges.

The carriage has deep grooves or gutters in which
the boards are dropped to admit the edge being planed
jointed or grooved. At the ends of these carriages are placed
soughs into which the shavings fall & are carried out of
the machine by a gate opening in the front bar.

Nov. 2, 1846.

The ~~beam~~ ^{beam} is to be made of wood & be pressed by means of a wedge, so as to fit, and the edge of the board raised as much as is necessary to be planed down to a ^{flat} ~~gape~~.

3rd A beam is back the rack supports the arm so spring pressing against the planed edge, the wing buttress against the beam with pressure of the spring against the plane may be increased by ^{the} wedge being cut. Thus accommodating more to the thickness of the shaving to wood.

There should be a spring to hold the carriage back to the wheel.
